UNITED STATES PATENT OFFICE.

RAY C. KLEFFMAN, OF IRENTON, MINNESOTA, ASSIGNOR OF ONE-THIRD TO WILLIAM SEAFIELD, OF IRENTON, MINNESOTA.

ROD-CLAMP.

1,048,705.

Specification of Letters Patent. Patented Dec. 31, 1912.

Application filed October 31, 1911. Serial No. 657,905.

To all whom it may concern:

Be it known that I, RAY C. KLEFFMAN, a citizen of the United States, residing at Ironton, in the county of Crow Wing and 5 State of Minnesota, have invented certain new and useful Improvements in Rod-Clamps, of which the following is a specification.

This invention relates to clamps especially 10 adapted to be used upon drill rods, and has for one of its objects to provide an effective clamp of simple structure which may be easily and quickly operated to grip the rod or release the same.

15 A further object of the invention is to provide in conjunction with the clamp a body forming a casing head portion for the same adapted to be attached to the end of well casing through which the rod is projected, the said body having ports through 20 which water and samples pumped from the bottom of a well may be passed.

25 A further object of the invention is to provide in the body a jaw mounted for movement transversely of the opening through which the rod passes, with means for moving the said jaw and holding the same in an adjusted position. Also a shaft 30 is journaled in the body and carries a jaw which is keyed thereon, suitable means being provided for turning the said shaft, whereby by its jaw is caused to impinge against the side of the rod and hold the same.

35 Still another object of the invention is to provide a rod clamping casing head having opposed rod-gripping members, one of said members being adjustable to accommodate a larger or smaller rod, and in this connection to provide means whereby the 40 jaw forming one of the rod gripping members may be readily removed when desired in order to replace it, or held from any accidental removal when in use.

45 A still further object of the invention is generally to improve this class of devices so as to increase their utility, durability and efficiency.

50 Further objects and advantages will appear in the following description, it being understood that various changes in form, proportions and minor details of construction may be resorted to within the scope of the appended claim.

55 For a full understanding of the invention reference is to be had to the following de-

scription and accompanying drawing, in which:

Figure 1 is a side elevation of the clamp; Fig. 2 is a sectional view of the same; Fig. 3 is a top plan view of the same; Fig. 4 is 60 a perspective view of a shaft used in the clamp; and Fig. 5 is a perspective view of a block used in the clamp.

Corresponding and like parts are referred to in the following description and indicated in all the views of the accompanying drawing by the same reference characters.

The clamp consists of a body 1 forming a casing head and adapted to be connected to the upper end of the well pipe. Said 70 body has a vertical passage 2 and the upper portion of the body is enlarged and transversely slotted as at 3. The lower portion of the body 1 is threaded for engagement with the upper end of a well casing 75 designated 4. Preferably the body has screw threaded engagement with the casing 4 so as to provide a permanent connection between the body and the casing. The body 1 is provided at a point below the slot 3 and 80 immediately above the screw threaded lower end with a port 5 which at its inner end enters the vertical opening 2 and terminates at its outer end at the surface of the said body. A jaw 6 is slidably mounted in the 85 inner portion of the slot 3. The jaw 6 is provided upon its back with inwardly disposed spaced flanges 7 and upon its front side with ridges or teeth 8. The side of the block carrying the teeth 8 is curved as 90 shown in the drawing. The body 1 is provided at the sides of the slot 3 and above the upper end of the vertically disposed opening 2 with inwardly disposed flanges 9 under which the jaw 6 may pass and which will prevent the jaw 6 from moving vertically out of the said slot when the said jaw is under the said flanges. When the jaw 95 is under the flanges 9 there is sufficient space for the jaw to be slipped vertically out of the slot 3 of the body 1. A screw 10 is threaded through the end of the body 1 at the inner end of the slot 3 and is provided at its inner end with a head 11 which is slidably received between the flanges 7 of 100 the jaw 6. This head 11 is of such shape that the screw is free to rotate with relation to the jaw but the jaw will move longitudinally with the screw. However, when the jaw is moved to the inner portion of the 105

110

slot 3 in the body 1 the flanges 7 and the said jaw may be moved transversely with relation to the screw and lifted out of the said slot. The screw 10 is provided at its outer end with a head 12 to which a wrench or other implement may be applied for the purpose of turning the screw.

It will be seen that this construction provides means whereby the jaw 6 may be shifted outward from beneath the lugs 9 so as to permit the jaw 6 to be vertically shifted and thus removed from its engagement with the screw 10. Thus the jaw 6 may be readily renewed or repaired whenever necessary. When the jaw 6 is shifted inward into its pipe-gripping position, however, it will be held from any vertical movement by the lugs 9 and thus can not be accidentally detached from the screw 10.

20 The body 1 is provided in its opposite sides at that end portion adjacent the outer end of the slot 3 with openings 13 which are notched as at 14 at their forward edge portions to permit the insertion of a key 17. 25 A shaft 15 is journaled in the openings 13 and is provided at its intermediate portion with a channel 16. A key 17 is seated in the channel 16 and a jaw 18 is mounted upon the intermediate portion of the shaft and is provided with a slot 19 which receives the key 17. A set screw 20 passes transversely through the jaw 18 and engages the intermediate portion of the shaft 15 and holds the jaw in position upon the shaft. The 35 inner end of the jaw 18 is cam shaped as at 21 and is provided with teeth or ridges 22. These teeth or ridges 22 are transversely disposed with relation to the teeth 8 carried by the jaw 6.

40 The ends of the shaft 15 project beyond the outer sides of the body 1 and are hexagonal or noncircular as at 23 in order that an operating lever 24 may be applied to one end. A foot treadle 26 of any desired pattern may be applied to the shaft.

By this arrangement of the parts of the clamp it will be seen that a drill rod 25 may be passed through the vertical opening 2 in the body 1 down into the pipe section 4 connected to the said body. By supporting the drill rod and its attachments the shaft 15 may be turned so that the jaw 18 will be carried away from the side of the rod. Then

the rod and its attachments may be lowered gradually and when in a desired position the shaft 15 may be turned so that the cam end 21 of the jaw 18 will be moved against the side of the rod 25. Thus the rod will be held against gravity in the position in which it is placed. By adjusting the screw 10 the jaw 6 is moved in the slot 3 to accommodate rods of different diameters. When it is desired to pump water or samples of material from the bottom of the well in which the tube 4 is located it is not necessary to remove the clamp from the upper end of the tube, for the reason that the water and the said material may pass up out of the pipe 4 and the body 1 through the vertical opening 2 and the port 5.

Having thus described the invention, what is claimed as new is:

A rod clamp comprising a body provided with a slot, a jaw pivotally mounted in the slot at one side of the body, a jaw slidably mounted in the slot at the other side of the body, the last mentioned jaw having at its outer portion inturned spaced flanges, the body having at the upper portion of its slot and at the opposite sides thereof inturned spaced flanges which are positioned from the end of the slot a distance greater than the transverse breadth of the last mentioned jaw plus the horizontal length of the flanges carried by the said jaw, the last mentioned jaw adapted to slide along the bottom of the slot and under the flanges carried by the body toward and away from the pivoted jaw, a screw bolt threaded through the body at one end of the slot and having a head which is received between the flanges carried by the slidable jaw, the parts being so arranged that as the screw bolt is turned the jaw with which it is in engagement is moved positively toward or away from the pivoted block and the slidable jaw adapted to be lifted out of the slot in the body when the said slidable jaw is beyond the edges of the flanges carried by the body and which project into the slot thereof.

In testimony whereof I affix my signature in presence of two witnesses.

RAY C. KLEFFMAN. [L.S.]
